United States Patent Office

Des. 184,371
Patented Feb. 3, 1959

184,371

TRACTOR SEAT

Arthur O. Radke, Wauwatosa, Wis., assignor to Bostrom Manufacturing Company, Milwaukee, Wis., a corporation of Wisconsin

Application May 19, 1958, Serial No. 50,952

Term of patent 14 years

(Cl. D14—6)

FIG. 1

FIG. 2

FIG. 3

FIG. 4

Figure 1 is a front view of a tractor seat embodying my new design;

Figure 2 is a top view thereof;

Fig. 3 is a side view; and

Figure 4 is a rear view thereof.

I claim:

The ornamental design for a tractor seat, substantially as shown.
